US00D934565S

(12) **United States Design Patent** (10) **Patent No.:** **US D934,565 S**
Wright et al. (45) **Date of Patent:** **** Nov. 2, 2021**

(54) **CASE FOR AN ELECTRONIC DEVICE**

(71) Applicant: **Catalyst Lifestyle Limited**, North Point (HK)

(72) Inventors: **Joshua Wright**, Hong Kong Sar (CN); **June Lai**, Hong Kong Sar (CN)

(73) Assignee: **CATALYST LIFESTYLE LIMITED**, Hong Kong (CN)

(**) Term: **15 Years**

(21) Appl. No.: **29/725,379**

(22) Filed: **Feb. 25, 2020**

(30) **Foreign Application Priority Data**

Nov. 28, 2019 (CN) 201930661009.0

(51) **LOC (13) Cl.** **03-01**

(52) **U.S. Cl.**

USPC **D3/298**

(58) **Field of Classification Search**

USPC D3/201, 207, 212, 215, 218, 269, 290, D3/294, 298, 299; D7/641; D13/108; D14/223

(57) **CLAIM**

The ornamental design for a case for an electronic device, as shown and described.

DESCRIPTION

FIG. 1 is a perspective view including the front, top, and side of a case for an electronic device;

FIG. 2 is a front elevation view of the case for an electronic device of FIG. 1;

FIG. 3 is a rear elevation view of the case for an electronic device of FIG. 1;

FIG. 4 is a side elevation of the case for an electronic device of FIG. 1;

FIG. 5 is an opposite side elevation view of the case for an electronic device of FIG. 1;

FIG. 6 is a top plan view of the case for an electronic device of FIG. 1; and,

FIG. 7 is a bottom plan view of the case for an electronic device of FIG. 1.

The broken lines in the drawings represent portions of the article that form no part of the claimed design.

1 Claim, 7 Drawing Sheets
